(57) **CLAIM**

The ornamental design for a shower pan, substantially as shown and described.

DESCRIPTION

FIG. 1 is a perspective view of the shower pan showing my new design;

FIG. 2 is a right side elevational view of the shower pan shown in FIG. 1;

FIG. 3 is a top plan view of the shower pan shown in FIG. 1; FIG. 4 is a rear elevational view of the shower pan shown in FIG. 1;

FIG. 5 is a left side elevational view of the shower pan shown in FIG. 1;

FIG. 6 is a front elevational view of the shower pan shown in FIG. 1; and,

FIG. 7 is a bottom plan view of the shower pan shown in FIG. 1.

The broken line rendering of portions of the article, defined with dashed lines, is included for the purpose of illustrating environmental structure and forms no part.

1 Claim, 2 Drawing Sheets
